DESIGN FOR A SPORTSMAN'S COMBINATION KNIFE AND UTILITY TOOL

John X. Peterson, Minneapolis, Minn.

Application February 9, 1948, Serial No. 144,368

Term of patent 14 years

(Cl. D22—3)

To all whom it may concern:

Be it known that I, John X. Peterson, a citizen of the United States of America, residing at 2215 Portland Avenue, Minneapolis, county of Hennepin, State of Minnesota, have invented a new, original, and ornamental Design for a Sportsman's Combination Knife and Utility Tool, of which the following is a description, reference being had to the accompanying drawings, forming part thereof.

Fig. 1 is a plan view of a sportsman's combination knife and utility tool showing my new design;

Fig. 2 is an elevational view showing one edge of the blade; and

Fig. 3 is a similar elevational view showing the opposite edge of the blade.

I claim:

The ornamental design for a sportsman's combination knife and utility tool, as shown.

JOHN X. PETERSON.
